(57) **CLAIM**

The ornamental design for a case for electronic communications device, as shown and described.

DESCRIPTION

FIG. 1 is a front perspective view of a case for electronic communications device, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detail view of the encircled region from FIG. 1.

The dot-dash broken line circle in FIGS. 1 and 9 delineates a portion of the case for electronic communications device that is part of the claimed design and that is shown on an enlarged scale in FIG. 9. The dot-dash boundary lines in FIGS. 1-2 and 5-6 delineate boundaries of the claim. The dashed broken lines throughout the drawing figures depict portions of the case that form no part of the claimed design.
